SAUNA BATH

Lauren Edgar Berry, 3150 21st Ave.,
Sacramento, Calif. 95822

Filed July 18, 1967, Ser. No. 8,200

Term of patent 14 years

(Cl. D83—1)

FIG. 1

FIG. 2.

FIG. 3.

This is a continuation-in-part of design application Ser. No. D. 4,244, filed Oct. 11, 1966 and now abandoned.

I claim:

The ornamental design for a sauna bath, substantially as shown and described.
